UNITED STATES PATENT OFFICE.

FREDERICK C. OVERBURY, OF NEW YORK, N. Y., ASSIGNOR TO FLINTKOTE MANUFACTURING COMPANY, OF RUTHERFORD, NEW JERSEY, A CORPORATION OF NEW JERSEY.

ROOFING-FASTENER.

978,334.

Specification of Letters Patent. Patented Dec. 13, 1910.

Application filed September 2, 1909. Serial No. 515,926.

To all whom it may concern:

Be it known that I, FREDERICK C. OVERBURY, of New York, in the county of New York and State of New York, have invented 5 certain new and useful Improvements in Roofing-Fasteners, of which the following is a specification.

This invention relates to means for securing roofing material to supporting surfaces 10 of a nature capable of receiving driven fastenings which penetrate the roofing material and are driven into the supporting surface which is generally of wood. By this I mean to distinguish from interlocking fastenings comprising two members one of 15 which is attached to the supporting surface and the other carried by the under side of the material and the two interlocked. Such devices may attain their object of avoiding 20 liability of causing leaking, but they are more expensive than driven fastenings and more difficult to apply.

The principal object of my present invention is to provide an improved fastener 25 which, while perfectly securing the covering material to the supporting surface, will permit of sufficient slip of the material relatively to the fastenings to prevent the material from buckling if it expands or contracts 30 under changes in atmospheric conditions, or due to length of exposure.

Another object of my invention is to provide fastenings of the driven type which 35 will secure weather-proof material to supporting surfaces, the fastenings connecting overlapping sections of the protecting material and also securing them to the supporting surface, but in such manner that every punctured part of a section of material is 40 protected, to prevent passage of water, either by an overlapping or underlying unperforated layer of material.

To these ends, the invention consists in the fastening, and in the combination, substantially as hereinafter described and claimed.

Of the accompanying drawings which 50 illustrate the invention for roofing purposes although it may be equally as well utilized in the sheathing of walls, Figure 1 is a perspective view of a portion of a roof structure having a well-known flexible material secured thereto by means of

one form of my improved fastening. Fig. 2 represents a section on line 2—2 of Fig. 1 on 55 a larger scale. Fig. 3 is a perspective view of the fastener shown in Figs. 1 and 2. Figs. 4, 5, and 6, are perspective views of modified forms of the fastener. Fig. 7 is a plan view of a portion of roofing material 60 held by the fastening shown in Fig. 5.

Similar reference characters indicate the same or similar parts or features in all of the views.

Referring first to Figs. 1, 2 and 3, the 65 supporting surface 10 may be understood as a portion of a roof structure on which the overlapping layers or strips of roofing material 11 are secured by my improved fastenings. Said strips are shown as of the 70 serrated type, having what are called in the trade "diamond" points 11^a. My invention is especially designed for this type of roofing material, as it provides for holding the points down without furnishing or causing 75 perforations communicating through the several layers to the support 10 such as would permit access of water through to said support. The invention is not limited, however, to this particular type of material. 80

The fastener comprises an elongated body 12 having an upwardly turned prong 13 and one or more holes 14 which furnish the means to enable the device to be attached to the supporting surface by suitable nails 15 85 driven through said holes.

Roofing in strip form is usually rolled up and when laid first has one end attached in proper position, and the succeeding fasteners are applied as the material is unrolled. 90 It will be readily understood that in the use of my present invention, each fastener is attached in position before the strip which is to overlie it is laid or unrolled. As it is unrolled, each upstanding prong 13 is 95 driven through it, and then said prong is bent down in a direction away from the point where the fastener has been attached to the supporting surface, so that the fastener as a whole lies almost in a continuous 100 plane. This act of bending the prong down, slightly lifts up the sheet material above the point where the prong has been forced through, as indicated at α in Fig. 2, the prong being preferably hammered down as 105 indicated at 13^x until it is almost in the

plane of the body portion 12, leaving only a slight offset which will permit the material to slip sufficiently along said offset portion to avoid buckling if the material expands, 5 and to avoid any enlarging of the aperture around the prong when the material contracts.

Instead of employing nails 15 passing through holes 14 in the body of the fastener, the means whereby the fastener may be attached to the supporting surface may comprise integral portions of said body. For instance the body may be of wire as at 12^a in Fig. 4, the ends being bent to form attaching points 15^a, an intermediate portion being bent to form an upwardly projecting prong 13^a the tip of which may if desired, be flattened sufficiently to enable it to be driven readily through the roofing material. 15 The device in this form is used in the same manner as has been described in connection with Figs. 1, 2 and 3.

In order to provide additional prong members which will serve to hold down the 25 points 11^a of the material, and still not interfere with the slip which has been described, I may provide a small strip of metal such as indicated at 16 in Fig. 5 having upturned prongs 16^a. This strip 16, 30 when used, is placed under the lower end of the body portion 12, so that when the roofing material is forced down over all three of the prongs 16^a and 13, the said prongs may bend down flat upon the material, as shown in 35 Fig. 7. As the strip 16 is free to slide in any direction relatively to the bar or body member 12 no obstruction to the slipping or sliding of the roofing material relatively to the body of the fastener is provided. 40 But this pronged strip 16 affords additional means for preventing the points 11^a of the roofing material from being loosened and turned up.

As shown in Fig. 6, the body 12^b need not 45 have an integral upturned prong. Instead, I may provide a three-armed plate 13^b, each arm of said plate being upturned to form prong 13^c. When said prongs 13^c are forced through the roofing material and 50 bent down in the direction above described, the slipping or sliding movement is provided for by reason of the plate 13^b being free to move in any direction under the lower end of the body 12^b.

55 In each form shown, the structure is such that the fastener presents an elongated portion which lies concealed under a strip of covering material and has means whereby it may be attached to a supporting surface, 60 one or more upwardly projecting prongs being provided which are out of alinement with the attaching means. Therefore, it is impossible for any moisture which might 65 find its way around the prongs, from working up to a point where it might find its

way through the underlying strips around the attaching means. At the same time, the holding prongs do not interfere with such expansion or contraction of the material as may occur under varying conditions of the 70 atmosphere, or due to the length of time that the roofing material has been laid, because of the direction in which they lie after the final act of bending is completed.

It will be understood that the several fasteners co-act with each other through the several overlapping layers of roofing material, so that each fastener is aided in its securing functions by adjacent fasteners. Each fastener is secured to the supporting 75 surface entirely underneath portions of the roofing material, and is so arranged that it will not only hold down the overlying section or strip of roofing material, but will permit that overlying section to expand 80 and contract without showing any buckling at the surface.

Having now described my invention, what I claim is:—

1. The combination with a supporting 90 surface of a plurality of strips or sheets of roofing material each having a serrated edge, a fastener comprising a single strip of material forming an elongated body portion constructed to lie concealed under said roofing 95 material, said fastener strip being provided with means whereby it may be attached to said supporting surface, one end of said fastener strip being arranged at an angle to the body thereof, and passed through one of the 100 serrated projections of the overlying roofing strip, said angular portion being flexible and bent in a direction away from said body to permit said roofing material to expand and contract without buckling between the prong 105 and the attaching means, the top face of said body being free of upwardly projecting protuberances.

2. The combination with a supporting 110 surface of a plurality of strips or sheets of roofing material each having a serrated edge, a fastener comprising a single strip of material forming an elongated body portion constructed to lie concealed under said roofing 115 material, and arranged to lie at right angles to said roofing strips, one end of each fastening being passed through one of the serrated projections of the overlying roofing strip, and continuing beyond the point of penetration in a direction in line with the body of the fastening, whereby said roofing material is free to expand and contract without buckling between the prong and attaching means.

3. The combination with a supporting 125 surface, of a plurality of overlapping strips of roofing material, and fasteners for securing said strips to the supporting surface, said fasteners having elongated portions concealed under the strips and having attaching means passed through portions of the strips 130

of roofing material which lie under the said elongated portions of the fasteners, said fasteners being provided with prongs out of alignment with the attaching means and projecting through overlying strips, said prongs continuing beyond the point where they pass through the strips, in a direction away from the points of attachment of the body por-

tions to permit the material to expand or contract.

In testimony whereof I have affixed my signature, in presence of two witnesses.

FREDERICK C. OVERBURY.
